UNITED STATES PATENT OFFICE.

CHARLES H. PFEIL, OF CHICAGO, ILLINOIS.

DESIGN FOR A FINGER-RING.

SPECIFICATION forming part of Design No. 16,684, dated May 11, 1886.

Application filed March 11, 1886. Serial No. 195,027. Term of patent 7 years.

To all whom it may concern:

Be it known that I, CHARLES H. PFEIL, a citizen of the United States of America, residing at Chicago, in the county of Cook and State of Illinois, have invented and produced 5 a new and original Design for Finger-Rings, of which the following is a specification, reference being had thereto to the accompanying drawing.

10 The drawing represents a perspective view, on an enlarged scale, of my newly - designed finger-ring.

The leading feature of my design is the central enlarged face having engraved the representation of a soldier, a sailor, and the Goddess of Liberty, and being surrounded by the 15 several insignia of war, and having upon each side the representation of an eagle with out-stretched wings, and beyond the same the representation of crossed cannons.

20 A is the finger-ring, the enlarged face B of which is circular, and bears upon its raised center, within a small circle, a, the figures of a soldier and a sailor shaking hands, a kneeling woman and a boy between, and the Goddess of

Liberty standing behind. This raised center piece, B, is surrounded by five points of a star with acorn-shaped ends, and in the enameled spaces between these star-points are arranged the insignia of war, as crossed muskets, guns, 30 sabers, trumpet, and anchor. On each side is engraved an eagle bordering with his head and spread wings the face portion, and at the feet of each eagle are represented a pair of cannons placed crosswise. 35

What I claim is—

The design for finger-rings herein shown and described, the same consisting of the central or top portion, B, having an annular base with a raised star thereon, a raised flat ring on the star, and the representation of an eagle on each side, adjacent thereto, and the representation of cross-cannons beyond, as shown. 40

In testimony whereof I affix my signature in presence of two witnesses.

CHARLES H. PFEIL.
